United States Patent Office

Des. 181,905
Patented Jan. 14, 1958

181,905

NARROW WOVEN FABRIC

Aaron Geffen, Woodmere, N. Y.

Application April 9, 1957, Serial No. 45,657

Term of patent 7 years

(Cl. D92—1)

Fig. 1

Fig. 2

Figure 1 is a plan view of a narrow woven fabric embodying my new design.

Figure 2 is a side elevational view thereof.

I claim:

The ornamental design for a narrow woven fabric, substantially as shown.
